CIGARETTE PACKAGE HOLDER

Horace Victor Farmer, Sault Ste. Marie,
Ontario, Canada

Application June 24, 1938, Serial No. 215,698

1 Claim. (Cl. 206—19.5)

The present invention relates to new and useful improvements in cigarette package holders for use particularly in automobiles and has for its primary object to provide, in a manner as hereinafter set forth, a device of this character embodying a novel construction for supporting a package of cigarettes in such a manner that a person, especially the operator of the vehicle, may conveniently remove the cigarettes from the package with one hand.

Another very important object of the invention is to provide a holder of the aforementioned character which is adapted to receive different kinds or types of cigarette packages.

Still another very important object of the invention is to provide a cigarette holder of the character described of such construction that a package of cigarettes may be expeditiously mounted thereon or removed therefrom.

Other objects of the invention are to provide a cigarette package holder which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in front elevation of an embodiment of the invention, showing one type of cigarette package mounted thereon.

Figure 2 is a vertical sectional view, taken substantially on the line 2—2 of Fig. 1.

Figure 3 is a side elevation of the device, showing another type of package mounted thereon.

Figure 4 is an elevational view of the device with the suction cup omitted.

Referring now to the drawing in detail, it will be seen that the embodiment of the invention which has been illustrated comprises a bar 1 of suitable resilient sheet metal. The bar 1 is preferably of substantially the shape shown to advantage in Fig. 3 of the drawing. On one end of the bar 1 is an integral clip 2 beneath which the back 3 of a cigarette package 4 is adapted to be slipped in a manner to be frictionally clamped thereby. At its free end, the clip 2 terminates in an outwardly curved lip 5 which facilitates the insertion of the cigarette package therebeneath. The lip 5 also assists in preventing the cigarette package from slipping down off the clip 2. At its

other or lower end, the bar 1 terminates in a flange or hook 6 which is engageable beneath the cigarette package in a manner to support same beneath the clip 2.

The bar 1 has formed in its lower portion an opening 7 and immediately adjacent said opening a longitudinal rib 8 is pressed out of said bar. The reference numeral 9 designates a rubber suction cup on which the bar 1 is rotatably mounted. The suction cup 9 is adapted to be mounted on any suitable smooth surface, such as the windshield or instrument board of an automobile.

Embedded in the suction cup 9 and projecting therefrom is a threaded, headed pin 10 on which the bar 1 is journaled, the opening 7 in said bar accommodating said pin. A nut 11 is threaded on the pin 10 for securing the bar 1 thereon. Mounted between the suction cup 9 and the bar 1 on the pin 10 is a resilient washer 12 having pressed thereinto a groove or channel into which the rib 9 on the bar 1 is adapted to snap for releasably securing said bar with the cigarette package thereon in an upright position. In Fig. 2 of the drawing, the groove or channel in the washer 12 which receives the rib 8 is designated by the reference numeral 13.

In use, the holder may be permanently mounted at a suitable point in the automobile which will be convenient to the operator sitting behind the steering wheel. To mount the package 4 on the holder, the back 3 of said package is simply slipped up under the clip 2 and the bottom of said package is engaged on the hook or flange 6. With the package 4 held in this position the closure 14 of said package may be conveniently opened and the cigarettes removed with one hand. An important and highly desirable feature of the invention is that the device is adapted to receive the cigarettes in the original packages.

In Fig. 3 of the drawing, the reference numeral 15 designates a paper type of cigarette package. When this type of package is to be mounted on the holder, a portion only of the top thereof is torn off in the usual manner, as at 16.

This side of the package 15 is then slipped up under the clip 2 and the bottom of the package is brought to rest on the hook or flange 6. Of course, the opening 16 which has been made in the top of the package receives the clip 2. To facilitate the entrance of the clip 2, several of the cigarettes are preferably removed from the package. As seen in Fig. 3 of the drawing, the construction and arrangement is such that the package 15 will be supported at an inclination

toward the side thereof in which the opening 16 has been formed for the removal of the cigarettes. Thus, due to the vibration of the automobile or by shaking the package 15 in any other suitable manner, such as by snapping it with a finger, the cigarettes therein will be caused to gravitate beneath the opening 16. Now, to remove the cigarettes, the bar 1 with the package 15 thereon is simply rotated on the pin 10 to an inverted position for permitting a cigarette to drop by gravity from said package through the opening 16. The package 15 and the bar 1 are then returned to an upright position. When this is done the rib 8 seats in the groove or channel 13 of the washer 12 for frictionally retaining the package in an upright position. The frictional contact between the bar 1 and the washer 12 may be regulated as desired through the medium of the nut 11 threaded on the pin 10.

It is believed that the many advantages of a cigarette package holder constructed in accordance with the present invention will be readily

understood and although a preferred embodiment of the device is as illustrated and described, it is to be understood that changes in the details of construction and in the combination and arrangement of parts may be resorted to which will fall within the scope of the invention as claimed.

What is claimed is:

A cigarette package holder comprising an attaching element adapted to be mounted on a support, a pin embedded in said element and projecting therefrom, a metallic bar rotatably mounted, at an intermediate point, on said pin, a metallic washer mounted on the pin between the element and the bar, said washer having a groove therein, a rib on the bar engageable in the groove for releasably securing said bar against rotation on the pin, a nut threaded on the pin for retaining the bar thereon and for frictionally engaging said bar with the washer, and means for detachably securing a cigarette package on the bar.
